UNITED STATES PATENT OFFICE

2,673,562

HYPODERMIC SYRINGE HINGING HEAD

Walter P. Wadinger, Cheshire, Conn., assignor to
 Scovill Manufacturing Company, Waterbury,
 Conn., a corporation of Connecticut

Application September 14, 1951, Serial No. 246,574

2 Claims. (Cl. 128—218)

1

This invention relates to hypodermic syringes of the kind adapted to receive and discharge a medicinal ampul and more particularly to hinging heads for such syringes.

One of the objects of this invention is to provide an improved hinging head which will be simpler in construction because made from a reduced number of parts thus lowering the cost of manufacture.

According to my invention the hinging head, including the side handles and pivot arms, is made as a unitary structure from sheet metal thus avoiding joints or seams such as would collect dirt or other injurious substances, and so facilitating the sterilizing of the same.

Other objects and advantages of my invention will be apparent from the following description of the device with one embodiment shown in the accompanying drawing wherein:

Fig. 1 is a side elevation of my improved hypodermic syringe.

Fig. 2 is a longitudinal sectional view through the same on an enlarged scale.

Fig. 3 is a sectional view similar to Fig. 2 of the upper part of the syringe showing the plunger hinged to one side for purposes of charging the syringe.

Fig. 4 is a sectional view taken along the line of 4—4 of Fig. 2, and

Fig. 5 is a perspective view of the yoke member, per se.

Referring now to the drawing there is provided a tubular casing or holder 10 having the lower end formed with an inward tapered portion 11 into which is fitted a female threaded bushing 12 and permanently held therein place as by soldering. Into this end of the holder 10 is detachably secured a hub 13 having a threaded section 14 for engagement with the threads of the female bushing 12. The hub 13 carries a tubular needle 15 extending from both ends of the hub, the longer outer part 15a of the needle serving to administer the hypodermic injection and the short inner part 15b serving to pierce the adjacent end of the ampul when inserted into the holder. The main body part of the hub 13 is provided with a knurled surface 16, and the smaller adjacent end of the taper section 11 terminates in a diameter not much larger than the knurled surface 16 of the hub 13. This is to facilitate the manipulation of the hub 13 in removing or assembling the same from the holder 10. The holder 10 is provided with a pair of opposed elongated openings 17 in order to permit visible inspection of the ampul when fitted therein.

2

The opposite end of the holder 10 is provided with a hinging yoke or head member 18 which comprises a cup-shaped housing 19 having an upper closed base end 20 with an opening 21 therein. The opposite open end of the cupped section is provided with integral opposed pivot arms 22 which extend axially relative to the cupped section and slightly offset outwardly of the diameter thereof and are adapted to straddle the holder 10. Also from the same open end of the housing 19 and half way between the pivot arms 22 is a pair of integral laterally extending handle arms or finger pieces 23 which are gripped by the operator in the operation of the syringe.

15 In order to hinge the yoke 18 to the holder 10 the upper end of said holder is provided with a pair of diametrically positioned piercings 24, and the free ends of the arms 22 are provided with trunnions 25 formed out of the material of the arms. As best shown in Fig. 4, these trunnions 25 are formed by an extruding operation wherein a punch is forced into the arms from their outer surface providing a recess 26 and on the opposite side of the arms forming up both an intermediate boss 27 and the trunnions 25, the latter being of a size to pivot in the piercings 24. The bosses 27 are provided to engage against the adjacent surface of the holder 10 and serve to hold the arms 22 spaced relative to said holder 10 to provide a free and easy hinging movement of the yoke 18 upon said holder. There is sufficient spring in the pivot arms and the barrel to allow them to be assembled by a snap action.

Thus all of the exposed parts of the heads including the housing 19, the handle arms 23 and the pivot arms 22 are just one unitary structure without seams or joints and which can readily be made by known sheet metal working methods.

In order to operate the syringe a plunger rod 30 is slidably fitted in the opening 21 of the yoke housing 19. The inner end of the plunger rod 30 is formed with an integral head 31 having a tapped hole 32 to which the threaded stem of a plunger (not shown) may be attached, the plunger always forming a part of the ampul. The opposite end of the plunger rod 30 has a thumb piece 33 permanently secured thereto in any conventional manner such as by threads 33a and a staking operation 33b.

To assure that the yoke 18 will be held in axial alignment with the holder 10 for operating the syringe, a slidable sleeve 34 is fitted into the housing 19 of the yoke 18. When the yoke 18 is aligned with the holder 10, the sleeve 34 is normally positioned to telescope within the open end of said holder 10 under the influence of a

3

spring 35 and thus lock the yoke 18 in aligned position with the holder 10. The spring 35 surrounds the plunger rod 30 and has one end seated against an interior flange 36 provided within the sleeve 34 and the opposite end abuts within the sleeve 34 and the opposite end abuts 5 the inner surface of the closed end 20 of yoke 18. The sleeve is limited in its movement into the body shell 10 by reason of the length of the trunnions 25 that project inwardly of the inner surface of the holder 10 and against which the sleeve can abut as a stop as best shown in Fig. 2.

In the operation of the device when it is desired to charge the holder 10 with an ampul the thumb piece 33 will be pulled outwardly to a position where the sleeve 34 will clear the end 20 of the holder 10 whereupon the yoke 18 and plunger 30 can be pivoted to one side to a position as shown in Fig. 3. It is to be noted that the upper end of the holder 10 is provided with a pair of opposed cutouts 37 so as to permit the yoke and plunger to be pivoted to either side of said holder leaving its open end free to be charged with the ampul. The yoke member will then be brought back into an aligned position with the body shell by manipulation of the handle members whereupon the sleeve 34 will automatically cam over either one of the cutouts 37 and when swung to aligned position will snap into the open end of the holder 10 to maintain such aligned position. The headed end of the plunger rod may then be secured to the plunger of the ampul and the syringe will then be ready for operation in the usual manner.

One form of the invention is presented herein for the purpose of exemplification but it will be appreciated that the invention is susceptible of embodiment in other structural modified forms coming equally within the scope of the appended claims.

I claim:

1. A hypodermic syringe comprising in combination a tubular casing, means at the lower end of said casing for carrying a needle, the upper end being open to receive an ampul, a hinging head for closing said upper end of the casing after insertion of the ampul comprising a hollow inverted cup-shaped housing of substantially the same diameter as the casing and having integral diametrically opposite handle arms extending laterally from its bottom portion and a pair of pivot arms embracing said upper end of said casing and also integrally joined to said housing between the handle arms, said pivot arms being hingedly connected to the case and offset laterally relative to the housing so as to swing freely over the end portion of said casing, a plunger slidably carried in said housing, and a spring-backed locking sleeve mounted in said housing for releasably holding said housing in alignment with said casing.

2. A hypodermic syringe comprising, in combination, a tubular holder, a head closing one end of said holder, means hinging the head to said holder comprising a pair of oppositely disposed arms extending from the head and embracing the adjacent end of said holder, and a boss projecting inwardly from the end portion of each arm and trunnions extending from said bosses into bearing recesses in said tubular holder.

WALTER P. WADINGER.
